UNITED STATES PATENT OFFICE.

PAUL EDWARD FISCHER, OF SCRANTON, PENNSYLVANIA.

ATTACHMENT FOR WARDROBE-TRUNKS.

1,373,320.

Specification of Letters Patent. Patented Mar. 29, 1921.

Application filed August 30, 1920. Serial No. 406,826.

To all whom it may concern:

Be it known that I, PAUL E. FISCHER, a citizen of the United States, residing at Scranton, in the county of Lackawanna and 5 State of Pennsylvania, have invented new and useful Improvements in Attachments for Wardrobe-Trunks, of which the following is a specification.

This invention relates to wardrobe trunks, 10 particularly to attachments therefor, and has for its object the provision of means associated with the drawers thereof whereby a drawer pulled out may be held in such pulled out position and be prevented from 15 dropping down so that placing of articles into or removal thereof from a drawer may be readily effected.

It is well known that in wardrobe trunks the drawers when pulled out to a slight extent will drop down, especially when full 20 and it is with this defect in view that the present invention has been designed. My invention contemplates providing means for supporting each drawer even though it be 25 pulled out to its maximum extent, my device facilitating the packing and unpacking of the drawers.

Another object is the provision of a drawer supporting structure of this character including slidably connected drawers, one of 30 which is rigidly secured at each side of the trunk and the other of which is detachably connected with each side of the drawer.

An additional object is the provision of a 35 structure of this character which will be simple and inexpensive in manufacture, which may be installed without making any alterations whatever in the construction of the trunk or drawer, which will be highly efficient in use, durable in service, and a general improvement in the art.

With the above and other objects and advantages in view, the invention consists in the details of construction to be hereinafter 45 more fully described and claimed and illustrated in the accompanying drawings in which—

Figure 1 is a front elevation of a wardrobe trunk in open position.

50 Fig. 2 is a longitudinal sectional view therethrough with the cover open and showing the drawers equipped with my device and in closed position,

Fig. 3 is a similar view showing a drawer 55 in open position,

Fig. 4 is a perspective view of the plate secured within the trunk,

Fig. 5 is a perspective view of the plate with which the drawer is detachably connected, and

Fig. 6 is a perspective view of the drawer removed.

Referring more particularly to the drawings, the letter A designates the sides of a wardrobe trunk between which are ordinarily mounted the drawers B. In ordinary conditions the drawers B are slidably mounted between the sides A but there is no provision for holding the drawers in suspended position while they are being packed 65 or emptied.

In carrying out my invention I provide a plate 10 which is secured within the trunk body at each side of the drawers therein and which is formed with a longitudinal 75 cut out portion 11 and which is also provided above and below this cut out portion with longitudinal slots 12 and 13. These plates are slidably secured in position by means of bolts 14 and 15 which are disposed 80 within the slots 12 and 13, respectively. By this means it will be seen that the plates 10 may be so disposed as to lie within the confines of the sides of the trunk or to 85 extend outwardly in front of them.

Associated with the ends of each drawer are plates 16 carrying bolts 17 slidably along the longitudinal cut out portion 11 of each plate 10. At its upper edge each plate 16 is formed with a slot 18 and an L-shaped 90 slot 19. Extending from each end of each drawer are pins or bolts 20 and 21, the former of which is engageable within the slot 18 and the latter of which is engageable within the slot 19 and it will be readily observed that this connection permits the drawer to be moved from association with the plates 16 when desired.

Under ordinary conditions the drawers, the plates 16, and the plates 10 are all disposed within the trunk entirely within the confines thereof so that the trunk may be closed in the usual manner. When the operator grasps the drawer and pulls it out the plates 16 associated therewith will also 105 be pulled out until the bolts 17 reach the ends of the cut out portions 11 whereupon the plates 10 will also be pulled out until their movement is stopped by engagement of the bolts 14 and 15 with the ends of the 110

slots 12 and 13. The drawer will then be supported in open position and may be packed or unpacked with ease.

From the foregoing description and a study of the drawings it will be apparent that I have thus provided a simply constructed and inexpensive drawer supporting structure which involves no alterations in the trunk construction itself but in which 10 the sliding members are located within the usual spaces between the sides of the drawers and the trunk body, the device being furthermore, easy to use, and very efficient in service.

15. While I have shown and described the preferred embodiment of my invention, it is of course to be understood that I reserve the right to make such changes in the form, construction, and arrangement of parts as 20 will not depart from the spirit of the invention or the scope of the subjoined claim.

Having thus described my invention, I claim:

A drawer supporting structure comprising a pair of plates disposed against the inner sides of an inclosing casing, and each formed centrally with a longitudinal cut out portion and being formed at opposite sides of said cut out portion with longitudinal slots, a second pair of plates disposed against the inner sides of said plates and carrying bolts slidable along said cut out portion, bolts passing through said slots and into the casing whereby said first named plates will be slidable with respect to the casing, said second named plates being provided in their upper edges with recesses, and securing members extending from the ends of the drawer and detachably seated within said recesses. 40

In testimony whereof I affix my signature
PAUL EDWARD FISCHER.
